(57) **CLAIM**

The ornamental design for a vertical integral climber, as shown and described.

DESCRIPTION

FIG. 1 shows a front view of the vertical integral climber.

FIG. 2 shows a right side view of the vertical integral climber.

FIG. 3 shows a left side view of the vertical integral climber.

FIG. 4 shows a rear view of the vertical integral climber.

FIG. 5 shows a bottom view of the vertical integral climber.

FIG. 6 shows a top view of the vertical integral climber.

FIG. 7 shows a perspective view of the rear face of the vertical integral climber.

FIG. 8 shows a perspective view of the front face of the vertical integral climber.

FIG. 9 shows a front view of the vertical integral climber of the FIG. 1, in an operational configuration.

FIG. 10 shows a right side view of the vertical integral climber of the FIG. 2, in an operational configuration.

FIG. 11 shows a left side view of the vertical integral climber of the FIG. 3, in an operational configuration.

FIG. 12 shows a rear view of the vertical integral climber of the FIG. 4, in an operational configuration.

FIG. 13 shows a bottom view of the vertical integral climber of the FIG. 5 in an operational configuration.

FIG. 14 shows a top view of the vertical integral climber of the FIG. 6, in an operational configuration.

FIG. 15 shows a perspective view of the rear face of the vertical integral climber of the FIG. 7, in an operational configuration.

FIG. 16 shows a perspective view of the front face of the vertical integral climber of the FIG. 8, in an operational configuration; and,

FIG. 17 shows a perspective partial view of the vertical integral climber.

The broken lines in the drawings are for the purpose of illustrating portions of the vertical integral climber that form no part of the claim.

This industrial design relates to a vertical integral climber to be used in fitness exercises and characterized by a proper and particular design with a practical and ornamental aspect.
